UNITED STATES PATENT OFFICE

ALBERT L. VEEDER, OF BOISE, IDAHO, ASSIGNOR TO V. & L. MILL AND FEEDER CORPORATION, OF BOISE, IDAHO, A CORPORATION OF INDIANA

HAMMER-TYPE MILL AND FEEDER

Application filed October 17, 1929. Serial No. 400,313.

This invention relates to a mill of the hammer type and to a feeder mechanism therefor.

It is aimed to provide a novel construction which will have greater capacity than existing types and which will operate more rapidly and will better operate in connection with hay and grain jointly, or separately.

A further object is to provide a novel construction wherein the hammers coact to form a V-shaped passage on the cylinders to lead the material to the center from each end of the cylinder in order to keep the grain or hay working toward the center of the cylinder.

A further object is to provide a novel construction of mill which will have a plurality rather than a single cylinder, arranged in coacting relation whereby one prepares the material for the other and will afford greater capacity in that the material will be finer when it enters the second cylinder and will leave the same more rapidly.

Further it is aimed to provide novel automatically operating clutch mechanism whereby the feeding is controlled in case of clogging or slowing down of operation of the working parts.

Various additional objects and advantages will become apparent from a consideration of the description following taken in connection with accompanying drawings illustrating an operative embodiment.

In said drawings:

Figure 1 is a view in side elevation of the improved feeder and mill.

Figure 2 is a vertical central sectional view through the feeder.

Figure 3 is a detail sectional view taken on the line 3-3 of Figure 6.

Figure 4 is a view partly in elevation and partly in section, illustrating the clutch mechanism of Figure 3 in connection with adjacent structure.

Figure 5 is a sectional view taken on the line 5-5 of Figure 6.

Figure 6 is a plan view of the improved feeder and mill.

Figure 7 is a central vertical sectional view through the mill, and

Figure 8 is a cross sectional view taken on the line 8-8 of Figure 7.

Referring specifically to the drawings, the parts constituting the invention may be supported upon a base or platform as at 10 and essentially comprise the hammer type mill as at A and a feeder mechanism as at B.

Referring specifically to the hammer type mill A and as detailed in Figures 7 and 8, the same comprises a vertically disposed casing 11 having means therein to cut hay or the like fed by the feeder mechanism B. In addition, grain may also be supplied into the casing 11 as through a hopper 13 arranged in communication with a chute 14 on the casing 11, a slidably and adjustable valve or bottom 15 being provided for the hopper to control the supply of the grain into the mill. By reason of the present construction, both grain and hay may be supplied to the mill at the same time, thus forming a mixture, or if desired, either grain or hay alone may be supplied to the mill.

Operating within the mill are upper and lower cylinders 16 and 17 which may comprise end disks 18 and 19, respectively, keyed to shafts 20 and 21, respectively, which are journaled in suitable bearings in the walls of the casing 11. Rods 22 and 23 connect the plates or disks 18 and 19 together and loosely mounted on each rod are a plurality of hammers 24. The hammers 24 each preferably consist of three arms or hammer heads 25, at the junction of which a triangular slot or opening 26 is provided. Such openings 26 enable the hammers to be strung and loosely mounted on the rods 22 in view of the fact that the openings 26 are relatively large with respect to the rods. The hammers thus have free movement on the rods and different heads alternately come into play and thus afford longer life for the hammers. It will be noted also that the heads 25 are disposed at angles to each other, thus forming between adjacent pairs, substantially V-shaped passages through which the grain and hay or either must pass and which serve to direct the same to the center of the cylinders and more effectively distribute it. Suitably fastened within casing 11 are foraminous concave

95

100

screens 27 and 28, that at 27 for the upper cylinder being of larger mesh than that at 28. The hammers 24 serve to engage the hay and grain or either adjacent the concaves 27 and 28, milling the same and causing it to pass first through the concave 27 and then through the concave 28. The concave 27 is larger than the concave 28, and the milling is more rapidly accomplished.

10 A bottom 29 is provided in the casing 11 having a central trough 30 in which an auger, screw or conveyor 31 is rotatably mounted, the same having a shaft 32 journaled in suitable bearings in the walls of the casing 11.

15 In order to operate the mill, a pulley 33 is provided on the shaft 20 and thereover a belt 34 may be trained, which is driven from any suitable source of power. Pulleys 35 and 36 are keyed to the shafts 20 and 21, respectively, and a twisted belt 37 is trained thereover whereby the cylinders are operated in opposite directions.

Another pulley 38 is keyed to the shaft 21 and is traversed by a belt 39 which also traverses a pulley 40 keyed to the shaft 32, whereby the conveyor 31 is operated. This conveyor 31 feeds the milled material to the side of the mill to be discharged into wagons, or any other means or location of disposition 20 for the milled material. It will be noted that the auger 31 is also equipped with fan blades 33 whereby the device will also serve as a fan or blower to assist in discharging the milled material.

25 It should also be mentioned that the lower cylinder is rotated faster than the upper cylinder for instance at a speed of two thousand revolutions per minute as compared with fifteen hundred revolutions per minute in order 30 to receive the ground material from the upper cylinder as fast as it is produced. In using the two cylinders and concaves, the material is milled in stages, that is it is discharged through the concave 27 coarser than 35 would be the case if it discharged through but a single concave. When it does discharge through the concave 27 it is relatively fine and is further milled and passed in a finer condition through the concave 28, the mill accordingly 40 having greater capacity and being capable of faster and more efficient operation.

Reverting to the feeder mechanism B, the same comprises a frame essentially having side boards 45 suitably connected together as 45 by bars 46, and connected also to the casing 11 adjacent the opening 12. Suitably journaled in appropriate bearings on the walls 45 are shafts 47 which have sprocket wheels 48 keyed thereto and which are in engagement with sprocket chains 49 constituting part of a raddle or endless conveyor generally designated 50 and which may be of any appropriate or conventional form. Operation of the raddle feeds hay which is supplied 55 thereto in the direction of the opening 12.

Adjacent such opening 12 and journaled in the walls 45 is a cutter-operating shaft 51 provided with a plurality of cranks 52 which are equi-distantly spaced about the axis thereof.

Journalized and suspended on each crank 52 70 is a cutter member 53, bearings 54 being bolted thereto as shown and overlapping the crank. Cutter members 53 may have depending toothed portions 55 thereon which are suitably sharpened and adapted to engage 75 the hay, which is disposed transversely of the raddle 50, as the same advances and feeds the hay toward the opening 12. Cranks 56 extend rigidly from the cutter members 53 and have pitmen 57 pivoted thereto at 58 80 and pivoted at 59 to the sides 45. In addition, feeder bars 60 are pivoted at 61 to the cutter members 55 and at 62 to links 63 carried by floating or vertically slidable blocks 66 guided in suitable frames 67 and normally 85 held in lowermost position by expansive coil springs 68, whose tension is regulated through the adjustment of screws 69 appropriately mounted.

At the lower ends, the blocks 66 have a 90 shaft 70 journaled therein and which extends outwardly through vertically elongated slots 71 provided in the walls 45. Keyed to the shaft 70 is a feed roll 72 for the hay which is arranged directly above a coacting feed roll 95 for the hay which is designated 73 and keyed to a shaft 74 appropriately journaled in the walls 45 and extending to the outside thereof.

As best shown in Figures 5 and 6, shaft 51 is provided with a drive pulley 75 which is 100 driven from a pulley 76 on the shaft 20 through the medium of a twisted belt 77. Such pulley is arranged on one side of the feeder mechanism B. On the opposite side of such feeder mechanism, a sprocket wheel 105 78 is keyed to shaft 51 and traversed by a sprocket chain 79 which also traverses a sprocket wheel 80 keyed to a shaft 81 suitably journaled on one of the walls 45 and which has a gear wheel 82 keyed thereto. A sprocket wheel 83 is also keyed to shaft 81 and is traversed by a sprocket chain 84 also traversing a sprocket wheel 85 keyed to the shaft 70. A tightener for the chain 84 is provided by a lever 86 pivoted at 87 to one of the boards or sides 45, carrying a sprocket wheel 88 at one end in mesh with the chain 84 and being subject to the action of a contractile spring 89, at its other end which spring is fastened to the lever 86 and the adjacent side 45. 110

The gear wheel 82 is in mesh with a gear wheel 90 keyed on a shaft 91 appropriately mounted and journaled on one of the sides 45 and which has a sprocket wheel 92 keyed thereto which is traversed by a sprocket chain 93, also traversing a sprocket wheel 94 rigid with gear wheel 90 and thus loose on shaft 93. A sprocket wheel 96 is also keyed to the shaft 95 and has a sprocket chain 97 traversing 120 125

ing the same and also traversing a sprocket wheel 98 keyed to the shaft 74.

The shaft 91 comprises concentric sleeves normally clutched together and the clutch is under control so as to automatically couple or release the sections in the event material should clog between the feed rollers 72 and 73 or if the speed of rotation of such rollers should diminish for any reason. To this end, 5 the gear 90 is loose on one of the sleeves of shaft 91 but normally clutched therewith through the engagement of a spring-urged pawl 96' carried by a disk 97 on the sleeve of shaft 91 opposite to that carrying the gear 10 wheel 90. Normally the pawl 96' engages 15 one of a plurality of projections 98 on the gear wheel 90, thereby maintaining the sleeves of shaft 91 connected together.

A governor mechanism 99 is driven from 20 the shaft 51 to control the engagement of the pawl 96' and projection 98. This governor comprises a shaft 100 having a worm 101 thereon keyed to a worm wheel 102 keyed on said shaft 51. A conventional governor device 102 is carried by shaft 100 so that centrifugal motion will cause a sleeve thereof 25 103 to move vertically on the shaft 100 and accordingly vary the position of or rock an arm 104 carried thereby and resting on a 30 portion of the feeder mechanism B and adapted at times to move at its free end 105 into a position where it engages or intercepts rotation of the pawl 96', moving it out of engagement with the adjacent pin 98, thus un- 35 coupling the sleeves of the shaft 91 whereby operation of the raddle 50 will cease since shaft 97 will not be driven. As a result, it will be seen that when the speed of the feed 40 rolls diminishes for any reason, the clutch controlling its drive is automatically thrown out of operation and which clutch will automatically be thrown back into operation upon the parts acquiring their normal speed.

Another governor mechanism is provided 45 whereby if undue resistance is offered to cutting on the part of the knives 55, their drive will be automatically thrown out. An automatic clutch also controls this operation. To this end, the pulley 75 has a plurality of govern- 50 nor arms 110 pivoted thereto at 111, each arm carrying a weight 112 which is adjustable along the arms. In addition, a link 113 is fastened at 114 to each arm 110 and is connected to a contractile spring 115 anchored at 55 116 to the pulley 75. Thus the springs 115 resist centrifugal action of the arms 110 in- 60 cidental to rotation of the pulley 75. The pulley 75 also has a clutch section 117 dis- 65 posed on the shaft 51, such clutch section and pulley 75 forming a unit which is loosely 70 mounted on the shaft 51. A loose intermediate clutch section 118 is also disposed on the shaft 51 and it is adapted to engage a clutch head 118^a fixed on shaft 51. The arms or 75 links 113 by means of pins 119 are connected

so that the centrifugal action of wheel 75 will control engagement of the clutch section 117, 118 and 118^a, the clutch mechanism being of such construction that disengagement is effected between the driving parts through the 70 resistance offered to the shaft 51 by inability of the knives 55 to operate.

The centrifugal action of the rotating member 75 causes the arms 110 to swing away from each other and the links 113 to thus exert 75 torsional action on the clutch member 117. Because the clutch member 118 is loose on shaft 51 it is freely slideable along the same but not rotatable independently thereof, and the engaging inclined or cam surfaces at 118^b 80 cause the clutch section 118 to slide and intimately and frictionally contact with the clutch section 118^a thus clutching the driving wheel 75 with the shaft 51 and causing the latter to operate. Should the motion of the driving member 75 diminish, the governor arms 110 will move toward the shaft and the reverse action to that traced will take place, thus disposing the parts in loose relation 85 without sufficient friction between clutch sections 118 and 118^a to drive the latter and accordingly shaft 51.

It will be seen that the two governors employed act independently of each other. The reason for such a construction is to enable 95 gradual cleaning out of hay from the feeder. For instance, the cutter knives and feed rakes start first, which takes the hay from the top of the supply on the raddle before it enters opening 12, and then the raddle and lower feed roll will start when the cylinder speed 100 becomes normal.

In order that access may be had to the various parts of the mill, for inspection, repair or the like, a door 120 is provided adjacent 105 the top thereof being hinged at 121. Likewise a door 122 is pivoted to such casing at 123 and it carries a baffle 124 on the inside thereof to aid in guiding the material being milled.

Particular attention is called to the fact that the adjustment of the feed bars 60 occurs simultaneously with the adjustment of the feed rollers 72 so that the adjustment of the feed rollers also effects corresponding adjustment of the feed bars 60. Such feed bars 60 are preferably toothed as shown at 125.

Various changes may be resorted to provided they fall within the spirit and scope of the invention.

I claim as my invention:—

1. A feeder mechanism of the class described comprising a feed member, a cutter movable relatively thereto, a feed bar associated with the cutter, feed rolls in advance of the feed bar, means adjustably mounting one of the feed rolls and to which the feed bar is connected whereby the latter 130

feed roll and feed bar will simultaneously be adjusted.

2. A feeder of the class described comprising a crank shaft, cutter members carried by the cranks of said shaft, links pivotally connected to the cutter members and to a fixed part, feed bars pivoted to the cutter members, links to which the feed bars are connected, slideable blocks to which the second mentioned links are connected, a feed roller carried by the blocks, a material feed member beneath the cutter members and bars, and a feed roller coacting with the first mentioned feed roller.
- 10 3. A machine of the class described having feed rollers, feeding means to move material thereto, and clutch means operable automatically to cease operation of the feeding means upon a decrease in speed of operation of the feed rollers.
- 15 4. A machine of the class described having first and second feeding means, and clutch means having a centrifugally operable part to cause automatic cessation of operation of the first feeding means when the second feeding means operates slow.
- 20
- 25

In testimony whereof I affix my signature.
ALBERT L. VEEDER.
